HONE TRUING DEVICE

Henry Robert Billeter, Highland Park, Ill., assignor to Ammco Tools, Inc., Chicago, Ill., a corporation of Illinois

Application July 24, 1951, Serial No. 238,315

3 Claims. (Cl. 51—67)

1

This invention relates to a hone truing device, and more particularly to such a device for truing the abrasive elements of rotatable hones of the type utilized for honing cylindrical surfaces.

Cylindrical hones of the type mentioned commonly employ a drive shank and honing head, the honing head having a plurality of abrasive elements that are expandable and contractible in radial directions. The hone may be mounted in various ways, such as in a machine which supports and rotates it, and the work piece to be honed is applied to the hone when so mounted. In the course of the use of the hone, the abrasive elements become worn and must be periodically trued.

An object of the invention is the provision of an improved device for truing the abrasive elements of rotatable hones of the type referred to.

Another object is the provision of a device for truing the abrasive elements of a rotatable hone of the character above referred to, which is adapted to be mounted on and supported by the drive shank of the hone in the truing operation and thereby effective for truing the abrasive elements to a shape perfectly concentric with the axis of the drive shank.

Another object is the provision of a device for truing the abrasive elements of a rotatable hone of the character above referred to, having a truing stone and adapted to be mounted on and supported by the drive shank of the hone in position wherein the truing stone is adjacent the abrasive elements, and which has elements engageable with the drive shank in such a manner as to be effective, upon manual pressure being applied to the device for retaining it on the hone, for positively limiting movement of the truing stone toward the abrasive elements.

A further object is the provision of a device for truing rotatable hones of the type having an elongated drive shank and a honing head with elongated abrasive elements therein, which when applied to the hone, is supported by the drive shank for movement back and forth along the drive shank in position for engaging the abrasive elements throughout the length of the latter.

Still another object is the provision of a device of the character referred to above for truing the abrasive elements of rotatable hones, which, being supported by the hone itself when applied thereto for performing the truing operation, enables the truing operation to be performed on the abrasive elements without the necessity of removing the hone from the machine in which it is mounted.

2

Another object is the provision of a device for truing the abrasive elements of rotatable hones, which is of exceedingly simple character.

A further object is the provision of a device of the aforesaid character, which is capable of being applied to a hone by a simple manipulation, by merely hooking the device onto the hone and holding it in position by manual pressure.

A still further object is the provision of a hone truing device of the character referred to, which contains a truing stone adjustably mounted therein and means for fixedly securing the truing stone in any desired adjusted position, within a predetermined range relative to the abrasive elements of the hone on which it is mounted, whereby the desired adjustment of the truing stone may be made according to the size of the hone or the adjusted position of the abrasive elements thereof, and the abrasive elements may thereafter be expanded toward and brought into engagement with the truing stone for removing portions of the abrasive elements to the depth necessary for eliminating irregularities of the abrasive elements so that the latter are shaped to a true, round and concentric shape.

Other objects will appear from the following description taken in conjunction with the accompanying drawings, in which:

Fig. 1 is a perspective view of the hone truing device applied to a hone mounted in a honing machine;

Fig. 2 is a perspective view of the truing device itself, with a small portion broken away and shown in section, this figure being greatly enlarged relative to the view of the device in Fig. 1;

Fig. 3 is a side view of the device applied to a hone; and

Fig. 4 is a view taken on line 4—4 of Fig. 3.

Referring in detail to the drawings, Fig. 1 illustrates the hone truing device applied to a cylinder hone. The hone may be mounted in any of a number of ways, it being shown herein as mounted in and supported by a honing machine. The hone truing device 12 will be described in detail later as to its details of construction and its use, but in order to provide the desired background for reference to the use of the device, a brief general description of the honing machine and hone will be given.

The honing machine 14 may of course be of any desired type, such for example as that disclosed in Mitchell Patent 2,483,590, issued October 4, 1949, and the hone 16 which is mounted in the honing machine, for truing which the truing device is applied, is of the type for honing internal

surfaces of cylinders. The hone 16 includes an elongated drive shank 18 and a honing head 20, the latter having a plurality of abrasive elements 22, sometimes referred to merely as stones, spaced circumferentially of the honing head and extending longitudinally substantially throughout the length thereof. The abrasive elements 22 extend radially outwardly of the honing head and have outer surfaces that are arcuate in cross-sectional contour, forming portions of a cylindrical surface. The hone 16 illustrated herein is of the type disclosed and claimed in my copending application filed July 31, 1951, Serial No. 239,526. The hone of that application, as well as hones of certain other types, includes a centering cone 24 rotatably and slidably mounted on the drive shank 18, and a drive adapter 25 for mounting the hone in the honing machine. The construction and arrangement is such that the drive adapter 25 rotates, which rotates the drive shank 18 and the latter in turn rotates the honing head 20. The drive shank 18 includes a push rod (not shown) which, upon axial movement thereof in one direction, expands the abrasive elements 22 radially outwardly. The push rod is actuated by certain devices within the honing machine 14 which are not shown herein but reference is directed to the above-mentioned Mitchell patent for the details thereof. The honing machine is provided with a treadle (not shown) connected with a chain 26, the latter being connected with a lever 28 for controlling the operation of the honing machine. Depression of the treadle is effective for expanding the abrasive elements of the hone, while the dial 30 is effective for setting elements of the machine for determining the extent of expansion of the abrasive elements produced by depression of the treadle. When the treadle is held in depressed position, the abrasive elements may be expanded and contracted directly by manipulation of the dial.

The truing device is made up of three simple main parts, namely, a rigid body member 32, a truing stone 34 supported therein, and a handle 36 which is utilized for the purpose of detachably securing the truing stone in the body member and providing a means for applying manual pressure to the device for maintaining it in proper position on the hone and sliding it back and forth along the hone.

The body member 32 is preferably an integral casting of aluminum alloy, but it may be made of any other desired material suitable for the purpose. The body member includes an inclined web portion 40 extending generally longitudinally of the body member and disposed to one side thereof. Extending laterally from the web portion 40 are two jaws 42 and 44 with their extended ends disconnected from each other, and spaced apart longitudinally along the body member a substantial distance, a distance greater than the diameter of the hone shank, for receiving the shank therebetween in applying the device to the hone in a manner to be referred to later. The jaws 42 and 44 are provided with V-shaped notches or concave surfaces 46 and 48 respectively, facing oppositely to each other for engaging opposite sides of the hone shank, and spaced apart in the direction of the diameter of the shank between said opposite sides sufficiently that when they engage the shank, the device extends generally longitudinally of the shank. The surfaces 46 and 48, although preferably of V-shape, may be of other shapes so long as they are

effective for engaging the hone shank so as to center the device on the hone.

The body member 32 also includes a portion for mounting the truing stone 34 and supporting the handle 36, which takes the form of an overhanging extension 50 which projects from the web portion 40 and the adjacent jaw 44 in a direction longitudinally beyond the latter. The extension 50 is at least as long as the honing head 10 on any of the bones with which the device is to be used so that the truing stone will engage the abrasive members of the bone throughout their length when the device is moved back and forth along the shank of the hone, as will be referred to later. The overhanging extension is substantially coextensive with the jaw 44 in transverse dimension and is preferably so disposed as to extend generally parallel with the longitudinal axis of the device as a whole. The extended end of the extension 50 is shaped to form a boss 52 having a central aperture 54 disposed on an axis transverse to the longitudinal axis of the device and radially with respect to the hone when the device is applied thereto. The truing stone 34 is 15 of appropriate size and shape to fit in the aperture 54 and as here shown is cylindrical. The truing stone may be made of any desired material so long as it possesses the required hardness for producing an abrasive action on the abrasive elements or stones 22. The truing stone itself may 20 therefore also be referred to as an abrasive element. In practice, a vitrified dressing stick, composed of silicon carbide grain bonded together, is employed as a truing stone. The stone 25 34 is adjustable along the axis of the aperture 54 and thereby adjustable transversely of the longitudinal axis of the device so as to be brought into the desired proximity to the abrasive elements 22 30 in the hone. It will be noted that the stone 34 35 extends in the same direction as the nearer jaw 44, whereby the stone is positively limited in movement toward the abrasive elements when the device is applied to the hone, as will be referred to later.

40 It is of course necessary that the truing stone when adjusted to the desired position be rigidly secured in that position, and to this end the handle member 36 is utilized for engaging and securing the stone in place. The handle is provided with a reduced threaded end 56 for threading into a tapped hole 58 in the boss 52 and engaging the stone 34. Upon tightening the handle the inner end thereof engages the stone and firmly retains the latter in position.

45 In the use of the device the handle is grasped by the hand, and the body member held in a position with its longitudinal axis substantially transverse to the axis of the hone. When the hone is 50 horizontally disposed for example, as herein shown, the body member is held in depending position, adjacent the vertical. The device is then moved toward the drive shank 18 so that the latter is inserted between the jaws 42 and 44 after which the device is rocked to the position wherein the 55 notches or concave surfaces 46 and 48 of the jaws engage the drive shank 18 on opposite sides thereof. The device may be applied to hones having shanks of various sizes by reason of the size and depth of the notches in the jaws 42 and 44. If the device, when applied to a hone having a given size shank, is disposed at an angle relative to the axis of the hone, any such angularity may be 60 readily compensated for by adjusting the truing 65 stone for moving it in the appropriate direction 70 75

in the aperture 54 for placing it in the desired proximity with the abrasive elements of the hone for performing the truing operation. The device is easily maintained in centered position by downward pressure on the handle 36 because the notches 46 and 48 engage the shank of the hone on opposite sides thereof at axially spaced points therealong. The notches in engaging the shank prevent lateral displacement of the device such as by twisting. The threads on the reduced end 56 of the handle are preferably right-hand threads so that the operator on applying downward pressure on the handle creates a normal tendency to thread the handle inwardly in the tapped hole 58 and thereby lock the stone 34. When the device is thus in position on the hone, the lower end of the truing stone is in a position adjacent the honing head and the stone can be adjusted radially with respect to the honing head (vertically as shown in the drawings) for the purpose of moving it to the desired position for the truing operation.

In the use of the device, it is applied to the hone in the manner above described while the machine is shut off so that the hone is not rotating. Then the machine is set so that the abrasive elements 22 of the hone are adjusted to a position slightly outwardly from their innermost contracted position. Such an adjustment, as reference to the above-mentioned Mitchell patent will show, is made by adjusting the dial 30 to the desired position while the treadle of the machine is depressed. The truing stone 34 is then adjusted downwardly so that it only touches the abrasive elements 22. The stone is then clamped in the adjusted position by tightening the handle 36.

After the foregoing steps and with the treadle retained in depressed position, the dial 30 is manipulated for fully retracting the abrasive elements 22. The operator bears downwardly on the handle 36 to stably support the device on the hone, and with the device so held, the next step is to set the honing machine into operation for rotating the hone. Thereafter the dial 30 is manipulated for expanding the abrasive elements 22 to a slight extent so that the abrasive elements are brought into position for engaging the truing stone upon rotation of the hone. The truing device is then moved back and forth along the drive shank 18 at a slow rate for engaging the abrasive elements by the truing stone throughout the full length of the abrasive elements. As noted above, the overhanging extension 58 is at least as long as the honing head of the hone with which the device is to be used. This enables the truing stone to fully reach the outer ends of the abrasive elements while the jaws are in engagement with the hone shank. For any given setting of the dial, the truing device is moved back and forth slowly and then the dial is again manipulated for slightly expanding the abrasive elements.

The operator continues expanding the abrasive elements and moving the truing device back and forth after each expansion until he is assured that the truing stone contacts each of the abrasive elements throughout its entire length and breadth. The abrasive elements after the operation described above will be dressed to a true arcuate shape in cross section concentric with the axis of the drive shank, and will be straight in longitudinal direction.

The honing machine 14 usually also includes an oil circulating system for directing oil onto the honing head during honing operations and it is desired also that oil be directed onto the honing

head during the truing operation. For this purpose the oil nozzle 60 on the end of a flexible conduit 62 of the oil circulating system is disposed so that the honing oil flowing therefrom is directed toward the honing head from the rear thereof for washing the grit from the abrasive elements and truing stone away from the shank.

The hone truing device of the present invention is especially effective for truing the abrasive elements of the hone to a shape perfectly concentric with the axis of the drive shank. This is made possible by virtue of the fact that the truing device is mounted on and supported by the drive shank itself. The concentricity of the abrasive elements with the axis of the drive shank has special significance in the operation of honing spaced, axially aligned bearing bushings by the use of the centering cone 24. Such centering cone is utilized in connection with honing piston pin bushings or other similarly aligned bushings. Reference is made to Zimmerman Patent 1,936,612, dated November 28, 1933, disclosing a hone having such a centering cone and disclosing the method of honing piston pin bearing bushings. In such operation, the piston is applied to the hone in such a way that the honing head extends through one of the bushings and into the other, and the centering cone is moved up to engage the adjacent bushing. The centering cone cooperates with the honing head in maintaining the piston in proper alignment with the axis of the drive shank of the hone, so that when the piston is alternatively positioned for honing each of the two aligned bearing bushings, the bushings will be honed perfectly concentric with the intended alignment axis of the bushings.

The centering cone is of course concentric with the axis of the drive shank and it is of course desirable that the outer surfaces of the abrasive elements be also concentric with the axis of the drive shank to accomplish the desired honing operation in the two aligned bearing bushings in the piston. The hone truing device of the present invention accomplishes such concentricity of the abrasive elements by reason of the fact that the device is supported directly by the drive shank. The abrasive elements are of course rotated about the axis of the drive shank and since the truing device is supported by the drive shank the truing device produces surfaces on the abrasive elements concentric with the axis of the drive shank. The back and forth movement of the device on the shank assures that such concentricity of the abrasive elements is established throughout the length of the abrasive elements.

Another advantage of the device of the present invention is that the hone can be trued while it is mounted and supported in the honing machine, eliminating the necessity for removing the hone from the machine for performing a truing operation. Since the hone itself provides the support for the truing device it is unnecessary to provide other and outside support for maintaining the truing device in proper position in the truing operation.

The device is exceedingly simple and inexpensive to make—it includes three simple main parts, the body, the truing stone and the handle. The truing device may be applied to the hone by a simple manipulation similar to a simple hooking movement.

The device is retained firmly in centered position on the hone merely by applying downward pressure on the handle 36. The pressure applied

to the handle by the operator produces such leverage that the jaws 42 and 44 on opposite sides of the shank, and spaced axially therealong, grip the shank in such a way that the device is easily maintained in stable position in the truing operation against the tendency of the abrasive elements of the hone to displace the device. As mentioned above, the truing stone 34 extends in the same direction as the nearer jaw 44. By reason of this relationship the stone is positively limited in movement toward the abrasive elements in response to manual pressure applied to the device in maintaining it on the hone. Rotation of the hone, in the initial portion of the truing operation, may have a tendency to cause the device to "bounce" i. e., throwing the truing stone away from the abrasive elements, but the pressure applied to the handle 36, being normally constant, causes the stone to be immediately returned toward the abrasive elements. However, the concave surface 48 in engaging the shank positively limits the movement of the truing stone toward the abrasive elements to the position intended according to the amount of material to be removed from the abrasive elements. There is therefore no possibility of the truing stone being moved toward the abrasive elements to an extent greater than that intended, with the result that an arcuate and true arcuate shape is produced on the abrasive elements. As the abrasive elements gradually assume their intended shape, any previously existing tendency of the abrasive elements to cause "bouncing" of the device is gradually dissipated until finally the device is held solidly and positively in its limit position for accurately shaping the abrasive elements.

I claim:

1. A device for truing a hone comprising a body, a pair of jaws carried by and projecting laterally from said body and having respectively, laterally concave, open and unobstructed, work-engaging surfaces facing in opposite directions and inwardly toward an axis passing medially across and between said jaws, said jaw faces being spaced longitudinally along and laterally from said axis, an abrasive element, said body having a portion longitudinally beyond one of said jaws carrying and guiding said abrasive element for adjustment toward and away from said axis, and means carried by said body for securing said abrasive element in adjusted position.

2. A device for truing a hone comprising a body, a pair of jaws carried by and projecting laterally from said body and having respectively, laterally concave, open and unobstructed, work-engaging surfaces facing in opposite directions and inwardly toward an axis passing medially across and between said jaws, said jaw faces being spaced longitudinally along and laterally from said axis, an abrasive element, said body having a projecting portion longitudinally beyond one of said jaws carrying and guiding said abrasive element for adjustment toward and away from said axis in a plane passing through said axis and medially of said faces, a handle member having a portion threaded into said body and engaging said abrasive element within said bore for securing said element in adjusted position and a portion extending perpendicularly to said body.

3. A device for truing a hone comprising a body having a web element, a pair of jaws carried by and projecting laterally from said web element and having respectively, laterally concave, open and unobstructed, work-engaging surfaces facing in opposite directions and in-

wardly toward an axis passing medially across and between said jaws, said jaw faces being spaced longitudinally along and laterally from said axis, an abrasive element, said body having an extension projecting from said web element longitudinally beyond one of said jaws carrying and guiding said abrasive element for adjustment toward and away from said axis, means carried by said extension for securing said abrasive element in adjusted position, and a handle projecting laterally from said extension.

4. A device for truing a hone comprising a body having a web element, a pair of jaws carried by and projecting laterally from said body and having respectively, laterally concave, open and unobstructed, work-engaging surfaces facing in opposite directions and inwardly toward an axis passing substantially parallel to said web portion and medially across and between said jaws, said jaw faces being spaced longitudinally along and laterally from said axis, an abrasive element, said body having an extension substantially parallel to said axis, projecting from said web portion longitudinally beyond one of said jaws carrying and guiding said abrasive element for adjustment toward and away from said axis, and means carried by said extension for securing said abrasive element in adjusted position.

5. A device for truing a hone comprising a body, a pair of jaws carried by and projecting laterally from said body and having respectively, laterally concave, open and unobstructed, work-engaging surfaces facing in opposite directions and inwardly toward an axis passing medially across and between said jaws, said jaw faces being spaced longitudinally along and laterally from said axis, an abrasive element, said body having a portion longitudinally beyond one of said jaws carrying and guiding said abrasive element for adjustment toward and away from said axis, a handle member having a portion threaded into said body and engaging said abrasive element for securing the latter in adjusted position and a portion projecting laterally from said body.

6. A device for truing a hone comprising a body, a pair of jaws carried by and projecting laterally from said body and having respectively, laterally concave, open and unobstructed, work-engaging surfaces facing in opposite directions and inwardly toward an axis passing medially across and between said jaws, said jaw faces being spaced longitudinally along and laterally from said axis, an abrasive element, said body having a bore longitudinally beyond one of said jaws carrying and guiding said abrasive element for adjustment toward and away from said axis in a plane passing through said axis and medially of said faces, a handle member having a portion threaded into said body and engaging said abrasive element within said bore for securing said element in adjusted position and a portion extending perpendicularly to said body.

7. Apparatus of the class described comprising a hone having a drive shank, a head carried by the shank and longitudinally aligned therewith, and an elongate abrasive surface carried by the head and parallel to the longitudinal center line thereof, and means for truing said abrasive surface including a body, a pair of jaws carried by and projecting laterally from said body and having respectively, laterally concave, open and unobstructed, work-engaging surfaces facing in opposite directions and inwardly toward an axis passing medially across and between said jaws,

said jaw faces being spaced longitudinally along said axis a distance sufficient to permit said shank to be rocked into position between and engaged by said faces, laterally apart a distance such that said shank is positioned with its center line substantially on said axis, an abrasive element, said body having a portion longitudinally beyond one of said jaws carrying and guiding said abrasive element for adjustment toward and away from said axis, and means carried by said body for securing said abrasive element in position to engage the abrasive surface of the hone.

8. Apparatus of the class described comprising a hone having a drive shank, a head carried by the shank and longitudinally aligned therewith, and an elongate abrasive surface carried by the head and parallel to the longitudinal center line thereof, and means for truing said abrasive surface including a body, a pair of jaws carried by and projecting laterally from said body and having respectively, laterally concave, open and unobstructed, work-engaging surfaces facing in opposite directions and inwardly toward an axis passing medially across and between said jaws, said jaw faces being spaced longitudinally along

5
10

said axis a distance at least as great as the transverse dimension of said shank and laterally apart a distance substantially equal to the transverse dimension of said shank, an abrasive element, said body having a portion longitudinally beyond one of said jaws carrying and guiding said abrasive element for adjustment toward and away from said axis, and means carried by said body for securing said abrasive element in position to engage the abrasive surface of the hone.
